REFRIGERATING APPARATUS

Filed Sept. 30, 1929

UNITED STATES PATENT OFFICE

HARRY F. SMITH, OF DAYTON, OHIO, ASSIGNOR TO FRIGIDAIRE CORPORATION, OF DAYTON, OHIO, A CORPORATION OF DELAWARE

REFRIGERATING APPARATUS

Application filed September 30, 1929. Serial No. 396,229.

The present invention relates to refrigerating systems and particularly to systems of the type in which a fluid other than the refrigerating medium is contained therein. In that type of system, this fluid is carried with the refrigerating medium and at times an excessive quantity thereof accumulates in such parts of the system where it will hinder the operation thereof or will cause parts of the system to be destroyed.

One of the objects of the present invention is to provide for positive return of the fluid to its proper place within the system.

In the specific embodiment I have illustrated the invention in connection with a refrigerating system of the compressor-condenser-expander type in which a quantity of lubricant is contained within the system. It is a more specific object of the present invention to provide positive and regular circulation of lubricant in refrigerating systems, and more particularly it is an object of the invention to separate the lubricant from liquid refrigerant within the evaporator and to return it to the compressor of a refrigerating system.

More specifically it is an object of the invention to utilize the velocity of gaseous refrigerant in a refrigerating system for operating a means which returns oil from the evaporator to the compressor thereof.

Further objects and advantages of the present invention will be apparent from the following description, reference being had to the accompanying drawing, wherein a preferred form of the invention is clearly shown.

In the drawing:

Fig. 1 is a diagrammatic view showing a refrigerating system having my invention embodied therein;

Fig. 2 is a vertical longitudinal section through a portion of the evaporator of such system;

Fig. 3 is a fragmentary top plan view taken on the lines 3—3 of Fig. 2; and

Fig. 4 is a sectional view taken on the lines 4—4 of Fig. 2.

For the purpose of illustrating the present invention I have shown in Fig. 1 a compressor-condenser-expander type of refrigerating

system having an evaporator 10 and a condensing element including a compressor 11, a condenser 12 and a receiver of liquid refrigerant tank 13. Refrigerant vapor is withdrawn from the evaporator through the vapor or low pressure conduit 14 and is liquefied in the condenser 12 and returned to the evaporator through the liquid or high pressure conduit 15. The compressor is operated by a motor 17 controlled by an automatic switch 18 which may be actuated in response to the refrigerating demand, for example by a pressure responsive device 19 connected to the low pressure conduit 14.

Referring to Fig. 2, evaporator 10 comprises a header 20 forming a reservoir for liquid refrigerant, and a plurality of tubes or ducts 21 depending from the header 20 for circulating refrigerant. The liquid refrigerant indicated by 22 is kept at a constant level 23 by a valve 24 actuated by a float 25. The liquid refrigerant is supplied by a connection 15a and the vapor or gaseous refrigerant is withdrawn through a connection 14a connected to the vapor conduit 14.

The apparatus, or system, as generally described above may be altered to suit conditions. Such systems, if of the compressor type, may be lubricated by placing a quantity of oil in the crankcase and depending upon the splashing of the rotating parts to distribute the oil throughout the compressor. Some of the oil is dissolved in the refrigerant and some of the oil is mechanically pumped by the compressor to the condenser and receiver and eventually to the evaporator. The refrigerant boils off in the evaporator, leaving the oil, which collects in a layer of from $\frac{1}{2}$ inch to $1\frac{1}{4}$ inches thick on top of the refrigerant.

Trouble has been experienced in the past because oil could not be separated from the liquid refrigerant and removed from the evaporator effectively. This accumulation of oil in the evaporator exhausts the supply of lubricant in the compressor thereby causing shaft seals to squeak and the bearings to be ruined. The large quantity of oil collected in the evaporator also cools and becomes very viscous thereby hindering evaporation of the

refrigerant. This is particularly harmful when the system is used to refrigerate an ice cream cabinet or the like wherein very low temperatures are desired to be maintained.

5 My invention is directed to a system whereby the circulation of oil therein will be positive and regular. In the particular application, I provide a device which utilizes the difference in viscosity, or the rate of flow over a wetted surface, of liquid refrigerant and lubricant to separate one from the other so that the lubricant, which is greater in viscosity, will adhere to the device and will be separated from the refrigerant within 10 the evaporator and conveyed to the outlet thereof. The oil extracted from the layer is then discharged into the vapor outlet conduit within the evaporator and is returned to the compressor along with gaseous refrigerant.

15 A conduit 30 projecting into the header 20 of the evaporator 10 is provided with a refrigerant gas inlet opening 31 located considerably above the level of the liquid refrigerant within the header to prevent the 20 entrance of liquid refrigerant into this opening. The portion of the conduit immediately surrounding the inlet opening 31 extends outwardly therefrom and has a scraper 32 formed at its end. The portion of the conduit between the scraper 32 and the opening 31 is formed to provide a trough 33. Two legs 34 soldered or welded onto the conduit 30 serve as bearings for receiving a pin 35 which carries a disk-like wheel 36. The 25 outer rim of the wheel 36 and a portion of its sides extend into the layer of oil on top of the liquid refrigerant contained in the header and communicates with the scraper 32. A worm gear 37 secured to the wheel 36 engages a worm 38 which is mounted on a 30 shaft 39 carrying a fan or turbine 40. The turbine 40 is enclosed within a circular extension 41 formed in the conduit 30. A venturi like orifice 42 is formed in the conduit 30 at the connection of the circular extended portion 41.

35 In the operation of the system, compressor 11 and condenser 12 liquefy the refrigerant which is collected in the liquid receiver 13 together with lubricant passing from the 40 compressor. The liquid refrigerant together with dissolved lubricant are admitted by means of the float valves 24 into the evaporator 10, and, as the refrigerant is 45 evaporated, the gaseous refrigerant is returned through the conduit 30, connection 14a and conduit 14 to the compressor 11. The oil in evaporator 10 floats on top of the liquid refrigerant after it has separated from the 50 liquid refrigerant by concentration through the constant evaporation of the refrigerant. The layer of oil on top of the refrigerant in the evaporator will at times also contain small globules of liquid refrigerant due to 55 the constant boiling and eruption of the re-

frigerant through the oil film. This necessitates absolute separation of the lubricant from the refrigerant before the lubricant can be conveyed to the outlet of the evaporator. Under the conditions of operation suction 70 produced by the compressor creates a flow of gaseous refrigerant through the conduit 30. The venturi like orifice 42, provided in the conduit 30, increases the velocity of the gaseous refrigerant and causes rapid rotation of the turbine 40. The turbine 40 actuates the shaft 39 and the worm 38, which meshes with the worm gear 37 provided on wheel 36, and causes the wheel to rotate. The speed of the wheel 36 is computed with respect to the relative viscosity of the liquid refrigerant and lubricant so that revolutions of the wheel is such that the lubricant will cling or adhere thereto during its operation while the liquid refrigerant will be vaporized or will flow 75 from the wheel back into the body of liquid contained in the header. The lubricant is thus separated from the liquid refrigerant and is conveyed by the wheel to the scraper 32 which removes the lubricant therefrom and deposits it in the trough portion 33 of the conduit 30. The conduit 30 then directs this oil into the inlet opening 31 of the conduit 30 from where it is returned to the crankcase of the compressor 11 along with the gaseous refrigerant. Should any liquid refrigerant be splashed into the conduit 30 during violent boiling within the header it will readily distill into a gaseous state due to the mass of metal comprising the conduit 30 which is connected with the end plate of the header through which heat is conducted to the conduit. Therefore only gaseous refrigerant along with lubricant, which enters the suction line 14, will be returned to the compressor. This prevents frosting of the conduit 10 which ordinarily occurs by the suction of liquid refrigerant into the conduit. It is apparent that the parts just described and particularly the operation of the rotating wheel 100 36 provides a mechanical moving device or means, that is, a means capable of mechanical operation or action which is actuated in response to the flow of refrigerant through a portion of the system or through the outlet 105 of the evaporator for separating lubricant from the refrigerant and for returning lubricant to the compressor by utilizing the difference in viscosity or the difference in rate of flow by gravity of the two liquids. 110

115 From the foregoing it is apparent that I have provided an apparatus which is infallible in its action and which functions more efficiently when the evaporator is endeavoring to maintain a very low temperature which low temperature increases the viscosity of the lubricant while at the same time increasing the adhesion thereof to the wheel utilized for extracting the lubricant from the evaporator. 120 My improved apparatus insures a positive 125

and regular circulation of oil contained in the refrigerating system. With this accomplished evaporators of the type disclosed are prevented from becoming oil-logged and are therefore more efficient for producing very low temperatures. Likewise the life of the compressor bearings are prolonged and the compressor shaft seal is prevented from squeaking.

5 10 While the form of embodiment of the present invention as herein disclosed, constitutes a preferred form, it is to be understood that other forms might be adopted, all coming within the scope of the claims which follow.

15 What is claimed is as follows:

1. A refrigerating system containing a quantity of refrigerant and lubricant, circulating means for the refrigerant, revolving means actuated by the flow of refrigerant in 20 a portion of the system for causing circulation of lubricant therein.

2. A refrigerating system comprising in combination, a refrigerant circuit having low pressure and high pressure sides, said circuit 25 containing a quantity of refrigerant and lubricant, revolving means actuated by the flow of refrigerant in the low pressure side for causing circulation of lubricant through said circuit.

3. A refrigerating system comprising in combination, a refrigerant circuit containing a quantity of refrigerant and another fluid and including a low pressure and a high pressure side, means communicating with the circuit for circulating refrigerant therein, and 35 revolving means actuated by the flow of refrigerant in the low pressure side for causing circulation of the other fluid contained in said circuit.

4. A refrigerating system comprising in combination, a refrigerant circuit having low pressure and high pressure sides, an evaporator, said evaporator containing a quantity of refrigerant and lubricant and having an inlet 40 and an outlet connected with the circuit, revolving means associated with the outlet of said evaporator for withdrawing lubricant from the evaporator to cause its circulation through said circuit.

5. A refrigerating system including a compressor and an evaporator, said evaporator having an outlet, conduit means connecting said outlet with said compressor, a revolving wheel within the evaporator for conveying 55 lubricant to the outlet thereof.

6. A refrigerating system including a compressor and an evaporator, said evaporator having an outlet connection and containing a quantity of liquid refrigerant and lubricant, 60 an inwardly extending conduit communicating with said outlet and having an opening, a revolving wheel adapted to convey lubricant toward the opening of said conduit to cause its return to the compressor.

7. A refrigerating system including a com-

pressor and an evaporator, said evaporator having an outlet connection and containing a quantity of liquid refrigerant and lubricant, an inwardly extending conduit communicating with said outlet, a wheel cooperating with said conduit adapted to discharge lubricant into the conduit to cause its return to the compressor, and means actuated by the flow of refrigerant from the evaporator for rotating said wheel.

8. A refrigerating system including a compressor and an evaporator, said evaporator having an outlet connection and containing a quantity of liquid refrigerant and lubricant, an inwardly extending conduit communicating with said outlet, a wheel cooperating with said conduit adapted to discharge lubricant into the conduit to cause its return to the compressor, and means located within the conduit actuated by the flow of refrigerant from the evaporator for rotating said wheel.

9. A refrigerating system including a compressor and an evaporator, said evaporator having an outlet connection and containing a quantity of liquid refrigerant and lubricant, an inwardly extending conduit communicating with said outlet connection and having an opening, a wheel cooperating with said conduit adapted to discharge lubricant into the conduit opening to cause its return to the compressor, means actuated by the flow of refrigerant through said conduit for rotating said wheel, and means for increasing the velocity of the refrigerant flowing through said first means.

10. A refrigerating system including a compressor and an evaporator, said evaporator having an outlet connection and containing a quantity of liquid refrigerant and lubricant, an inwardly extending conduit communicating with said outlet connection and having an opening, a wheel cooperating with said conduit adapted to discharge lubricant into the conduit opening to cause its return to the compressor, means actuated by the flow of refrigerant through said conduit for rotating said wheel, said conduit having a venturi like orifice for increasing the velocity of the refrigerant flowing through said actuating means.

11. A refrigerating system including a compressor and an evaporator, said evaporator having an outlet connection and containing a quantity of liquid refrigerant and lubricant, an inwardly extending conduit communicating with said outlet connection and having an opening, a wheel cooperating with said conduit adapted to discharge lubricant into the conduit opening to cause its return to the compressor, a turbine actuated by the flow of refrigerant through said conduit for rotating said wheel, and means for increasing the velocity of the refrigerant flowing through said turbine.

12. A refrigerating system including a com-

compressor and an evaporator, said evaporator having an outlet connection and containing a quantity of liquid refrigerant and lubricant, an inwardly extending conduit communicating with said outlet connection and having an opening, a scraper adjacent the opening in said conduit, a wheel cooperating with said scraper adapted to discharge lubricant into the conduit opening to cause its return to the compressor, and means actuated by the flow of refrigerant through said conduit for rotating said wheel.

13. A refrigerating system including a compressor and an evaporator, said evaporator having an outlet connection and containing a quantity of liquid refrigerant and lubricant, an inwardly extending conduit communicating with said outlet connection and having an opening, a scraper adjacent the opening in said conduit, a wheel cooperating with said scraper adapted to discharge lubricant into the conduit opening to cause its return to the compressor, means actuated by the flow of refrigerant through said conduit for rotating said wheel, and means for increasing the velocity of the refrigerant flowing through said first means.

14. An evaporator of a refrigerating system having an outlet and containing a quantity of liquid refrigerant and lubricant, mechanical moving means utilizing the difference in viscosity of the liquid refrigerant and lubricant on said mechanical moving means for separating the lubricant from the refrigerant and for conveying said lubricant to the outlet of the evaporator, said mechanical moving means being actuated by the flow of refrigerant through the outlet of the evaporator.

15. An evaporator of a refrigerating system having an outlet and containing a quantity of liquid refrigerant and lubricant, means including a wetted surface utilizing the difference in rate of flow by gravity on the wetted surface of the liquid refrigerant and lubricant for separating the lubricant from the refrigerant and for conveying said lubricant to the outlet of the evaporator.

16. A refrigerating system containing a quantity of refrigerant and another fluid and including an evaporator, said evaporator having a continuously open outlet, circulating means for the refrigerant, mechanical moving means actuated by the flow of refrigerant through said continuously open outlet for causing circulation of the other fluid contained in the system.

17. A refrigerating system containing a quantity of refrigerant and lubricant and including an evaporator, said evaporator having a continuously open outlet, circulating means for the refrigerant, mechanical moving means actuated by the flow of refrigerant through said continuously open outlet for

causing circulation of lubricant through said system.

18. A refrigerating system containing a quantity of refrigerant and another liquid, circulating means for the refrigerant, mechanical moving means actuated by the flow of refrigerant in a portion of the system for causing circulation of the other liquid contained in the system by utilizing the difference in rate of flow by gravity of the refrigerant and the other liquid on said mechanical moving means.

19. An evaporator of a refrigerating system having an outlet and containing a quantity of liquid refrigerant and lubricant, mechanical moving means utilizing the difference in rate of flow by gravity of the liquid refrigerant and the lubricant on said mechanical moving means for separating the lubricant from the liquid refrigerant and for conveying said separated lubricant to the outlet of the evaporator, said mechanical moving means being actuated by the flow of refrigerant through the outlet of the evaporator.

20. A refrigerating system including a compressor, a condenser, and an evaporator operatively connected together, a body of liquid in said evaporator, revolving means communicating with said body of liquid in said evaporator, said revolving means being actuated by the flow of fluid from the evaporator to the compressor for causing circulation of the liquid contained in said evaporator.

In testimony whereof I hereto affix my signature.
